John Aug. Myers,

UNITED STATES PATENT OFFICE.

JOHN AUGUST MYERS, OF BRADDOCK, PENNSYLVANIA.

DOUBLE-NECKED RAIL FOR RAILWAYS.

No. 887,832.

Specification of Letters Patent.

Patented May 19, 1908.

Application filed June 29, 1907. Serial No. 381,565.

To all whom it may concern:

Be it known that I, JOHN AUGUST MYERS, a citizen of the United States, residing at Braddock, county of Allegheny, and State of Pennsylvania, have invented a new and useful Double - Necked Rail for Railways, of which the following is a specification.

- My invention relates to improvements on double necked rails for railways to be made 10 in different sizes showing the possibility of rolling them as indicated in Figure 2 of this drawing. I attain this object by the structure illustrated in the accompanying drawing in which
- 15 Fig. 1, is the end view of the finished rail. Fig. 2, is also the end view showing the position of the rail during the rolling process whereby the recess *e*, is formed on bottom plate *c*, and the formation of the two necks 20 which will leave a hollow space between the two, when the same are pressed into their respective places.
- Similar letters refer to similar parts throughout the several views.
- 25 Fig. 1, gives the end view of the finished rail with the two necks marked *a*, & *b*, forming the hollow space between the two necks, the foot plate *c*, of the rail showing the recess *e*, on the same, formed by the corner *f*, on the 30 bottom plate for receiving the lower inside edge of neck *b*, and the pressed corner *d*, which later will be completed in the last

passes of the finishing rolls, whereby parts of the material is pressed down to form said corner, which will hold the lower edge of neck *b*, in its right position. The side marked *g*, on the head *i*, is not so deep as the side marked *h*, all plainly shown in these figures and described.

Fig. 2, shows the position of the rail 40 during rolling and how the head *i*, is placed to the side so that the hollow space becomes larger and the neck *a*, higher fully as described, the dotted lines in these figures indicating the shape of the rail formed in the last 45 pass of rollers when finished substantially as set forth.

I am aware that prior to my invention double necked rails for railways have been made, I therefore do not claim such a combination broadly but

What I do claim as my invention and desire to secure by Letters Patent is,

A rail having double necks spaced apart, a head, and a recessed bottom plate, one of 55 said necks being continuous with the bottom plate and head and the other extending from the head and adapted to be received in the recess of the bottom plate and be compressed therein, substantially as set forth.

JOHN AUGUST MYERS.
